UNITED STATES PATENT OFFICE.

CHARLES B. LINDSEY AND DAVID N. GODDARD, OF MOUNT VERNON, ILL.

HAME-TUG.

SPECIFICATION forming part of Letters Patent No. 310,693, dated January 13, 1885.

Application filed April 26, 1884. (No model.)

To all whom it may concern:

Be it known that we, CHARLES B. LINDSEY and DAVID N. GODDARD, citizens of the United States, residing at Mount Vernon, in the county of Jefferson and State of Illinois, have invented a new and useful Hame-Tug, of which the following is a specification, reference being had to the accompanying drawings.

Our invention relates to hame-tugs; and it has for its object to provide the sections of the same with improved means for the attachment of the plate carried by the trace, whereby the same may be readily attached to and detached from said hame-sections, and yet in such manner that they will be securely held therein when attached, and all liability of their displacement being overcome.

A further object of the invention provides improved means for connecting the tugs or sections one to the other, and, further, to provide devices of this character which shall be simple in their construction, which shall be durable in use, and may be manufactured and supplied at a slight cost.

With these ends in view the invention consists in the peculiar construction of slot for the reception of the trace-plate, and in the construction of the trace-plate to be connected therewith.

The invention further consists in certain details of construction and combinations of parts, hereinafter fully described, and pointed out in the claim.

In the drawings, Figure 1 is a side view showing my improved hame-tugs connected, showing the trace-plate connected therewith. Fig. 2 is a perspective view of the trace-plate and one of the hame-sections, and Fig. 3 is a detail view of a modified form of hame-tug and trace-plate.

In the accompanying drawings, in which like letters of reference indicate corresponding parts in the several figures, A represents the hames, which are preferably cast, and made substantially rectangular in form. These hame-sections A are formed with downwardly-extending sides, which said ends project outwardly beyond the body portion at one end, and are connected by means of a transverse bar, b, for the attachment of the hook of the adjacent section, as will be more fully described. At about the center of the hame-

tugs, and upon the upper side thereof, is provided an opening, which approximates the form of a Roman cross, as clearly shown. The 55 opposite end of the hame section or tug is provided with an outwardly-projecting extension, which is turned downwardly to form a hook, B, said hook being adapted to engage the transverse bar of the next adjacent section.

C represents the trace-plate, which is slightly reduced at the point of its attachment to the trace, and is provided with perforations for the passage of rivets or other suitable securing means. Upon the under side of the forward end of this trace-plate C is provided a downwardly-projecting lug, D, which has formed integral therewith, and projecting at right angles thereto from either side, a cross-piece, d, which is flush with its upper edge. It will thus be seen that the trace-plate is provided with means for its attachment to the hame tugs or sections to correspond with the opening of the hame-tug, which, as before mentioned, is of a Roman-cross shape.

In the operation of the above-described devices the hame-sections are connected one with another by means of the hooked ends engaging the transverse bar on the next adjacent section. The lug on the under side of the trace-plate is then inserted in the opening of the hame-tug and drawn to the rear end thereof, the cross-strip bearing against the under sides of the tug in rear of the transverse opening. The drawing or pulling of the lug on the trace-plate is allowed by reason of the longitudinal slot in the hame-section being longer than the corresponding-shaped lug upon the said trace-plate. By this means of securing or attaching the trace to the hame-sections all liability of the disengagement is prevented and a reliable and efficient attaching means provided.

In Fig. 3 we have shown a modification, in 95 which case the slot upon the hame-sections are rectangular in form, and the trace-plate provided with a correspondingly-shaped lug of somewhat smaller dimensions. In this case the lug on the under side of the said trace-plate 100 is inserted by first passing one end of the lug into the opening and to the forward end thereof, and then dropping the remaining portion of the lug into said opening. When draft is

applied, all possibility of their separation is prevented.

It will be seen from the above description that by the use of the devices constructed by us an effective and reliable means for the connection of the hame-sections is provided, and also that the means for the attachment of the trace-plate are simple, thoroughly efficient, and easily attached to or detached from one another.

We are aware that previous to our invention hame-tugs have been provided with a hook at one end and a cross-bar at the other end to receive the hook of the adjacent tug.

We are also aware that hame-tugs have been provided with various forms of openings to receive a correspondingly-shaped lug of the trace-plate. Our invention differs from these, however, in the peculiar formation of the hame-tug opening and trace-plate lug to engage the same; hence we make no broad claim to the construction shown and described; but,

Having fully described our invention, what

we claim as new, and desire to secure by Letters Patent, is—

As an improvement in hame-tugs, the herein-described adjustable tug, comprising a series of detachable sections, each of which is provided with an opening in the form of a Roman cross, as shown, in combination with the trace-plate C, having a downwardly-projecting lug, D, provided with a cross-piece, d, formed integral therewith and projecting at right angles thereto, said cross-piece being flush with the upper edge of the lug and adapted to hold the trace-plate in its adjusted position, as set forth.

In testimony that we claim the foregoing as our own we have hereto affixed our signatures in presence of two witnesses.

CHARLES B. LINDSEY.
DAVID N. GODDARD.
